(57) **CLAIM**

The ornamental design for an atomizer bottle, as shown and described.

DESCRIPTION

FIG. 1 is a front perspective view of a first embodiment of an atomizer bottle;

FIG. 2 is a front view thereof;

FIG. 3 is a back view of the atomizer bottle of FIG. 1;

FIG. 4 is a right side view thereof;

FIG. 5 is a left side view thereof;

FIG. 6 is a top view thereof;

FIG. 7 is a bottom view thereof; and,

FIG. 8 is a perspective view thereof, showing the atomizer bottle in a position of use with a nozzle and an atomizer bulb. The broken lines are shown for the purpose of illustrating unclaimed environment and unclaimed portions of the atomizer bottle and form no part of the claimed design.

1 Claim, 8 Drawing Sheets
